US00D842303S

(12) **United States Design Patent** (10) Patent No.: **US D842,303 S**
Man (45) Date of Patent: ** Mar. 5, 2019

(54) **PORTABLE HANDHELD RADIO
FREQUENCY TAG READER**

(71) Applicant: **Megabyte Limited**, Hong Kong (HK)

(72) Inventor: **Chun Sing Matthew Man**, Hong Kong (HK)

(73) Assignee: **Megabyte Limited**, Hong Kong (HK)

(**) Term: **15 Years**

(21) Appl. No.: **29/591,001**

(22) Filed: **Jan. 16, 2017**

(30) **Foreign Application Priority Data**

Jul. 14, 2016 (HK) 1601349

(51) **LOC (11) Cl.** **14-02**

CLAIM

The ornamental design for a portable handheld radio frequency tag reader, as shown and described.

DESCRIPTION

FIG. 1 is a first perspective view of a portable handheld radio frequency tag reader showing my new design; FIG. 2 is a second perspective view thereof; FIG. 3 is a front elevational view thereof; FIG. 4 is a rear elevational view thereof; FIG. 5 is a right side view thereof; FIG. 6 is a left side view thereof; FIG. 7 is a top plan view thereof; and, FIG. 8 is a bottom plan view thereof.

1 Claim, 8 Drawing Sheets
